UNITED STATES PATENT OFFICE

170,612

SERVICE MAN'S CHEST

James T. Shepler, North Hollywood, Calif.

Application May 21, 1952, Serial No. 19,808

Term of patent 14 years

(Cl. D58—12.6)

To all whom it may concern:

Be it known that I, James T. Shepler, a citizen of the United States of America, residing at North Hollywood, county of Los Angeles, State of California, have invented a new, original, and ornamental Design for Service Man's Chest, of which the following is a specification, reference being had to the accompanying drawing, forming a part thereof.

The figure is a front perspective view, from above, of a service man's chest embodying the design of my invention.

The rear wall and the bottom of the chest are plain and conventional. The side of the chest not shown is substantially a mirror image of the side shown.

The dominant feature of my design resides in the portions shown in full lines.

I claim:

The ornamental design for a service man's chest, as shown and described.

JAMES T. SHEPLER.
